(57) **CLAIM**

I claim the ornamental design for a nestable industrial metal cathode for the mining industry, as shown and described.

DESCRIPTION

FIG. 1 is a top perspective view of the first embodiment of a nestable industrial metal cathode for the mining industry showing my new design;

FIG. 2 is an enlarged section al view of a corner thereof taken along line 2—2 of FIG. 1;

FIG. 3 is a bottom perspective view thereof;

FIG. 4 is a top perspective view of the second embodiment of a nestable industrial metal cathode for the mining industry showing my new design;

FIG. 5 is a bottom perspective view thereof; and,

FIG. 6 is a top perspective view of the third embodiment of a nestable industrial metal cathode for the mining industry showing my new design.
